UNITED STATES PATENT OFFICE

2,430,214

PNEUMATIC DEVICE FOR THE MANUFACTURE OF GLUED SHOES

Carlos Fernando Delsordo, Mexico City, Mexico

Application May 4, 1945, Serial No. 592,034
In Mexico July 27, 1944

2 Claims. (Cl. 12—33)

2

1

This invention refers to apparatus for the manufacture of shoes, especially for the manufacture of such shoes as are known by the name of "glued shoes," and more particularly to pneumatic apparatus or presses for gluing the sole in the manufacture of glued shoes.

Thus far, in connection with known apparatus, it is required to employ special devices for each case in the gluing of the sole of the shoes made according to that system, and, in fact, plain shoes for children and men require the masses of gluing to be of a certain type and shape; which type and shape have to be different in the case of low-heeled shoes for gentlemen and ladies; and they also have to be different for the manufacture of ladies' high-heeled shoes, it being required by makers to have a set of plates to be changed on their respective machines. With the improved device of my invention, the advantages of which will be easy and immediate to appreciate by experts, the inconveniences pointed out will be entirely eliminated, in view of the fact that the plate or surface supporting the pressure of the shoe on the pneumatic cushion, supplies over the zone of the heel such height as may be had by the last of the different kinds of shoes above mentioned. The curved space between the heel and the floor; that is to say, the hollow portion of the shank, is filled by the pneumatic chamber through the force of air and the pressure of the shoe with its last.

From above, it will be seen that the main object of the invention is to provide a press for the manufacture of the glued-shoe, which constitutes an improvement, having the advantage of being provided with means whereby the same apparatus can be used for the manufacture of men's and children's glued shoes requiring a level plane, and women's shoes provided with the highest heels in use, inasmuch as the portion corresponding to the heel in the said apparatus can be raised to any height required by the last of the shoe.

In the present device of my invention, the point of the shoe can distinctly be put either forward or backward, by simply changing the position of the respective bridges or holders.

These and other advantages, details and features of the apparatus of my invention will become evident from the following description, as well as from the attached drawings accompanying it by way of illustration, the same referring it by way of illustration, the same referring characters being used to show the same portions of the two figures shown.

In the drawings:
Fig. 1 shows an elevation of an apparatus made in accordance with my invention, the surface or plate over which the pneumatic cushion is placed being shown complete, and its longitudinal section showing the structure supporting the said plate as well as the mechanism raising the backward half of same, and

Fig. 2 is a conventional detail in perspective of the mechanism used to raise the backward half of the plate for the gluing in accordance with this apparatus.

Before proceeding to the description in a detailed manner of the apparatus invented by me, I wish it to be well understood that the drawings illustrate only by way of example the preferred manner in which this invention is practised, for which reason the invention is not restricted exclusively to the specific details herein illustrated and described. It is possible, therefore, to make changes and alterations in the arrangement and form of its parts, to meet the requirements made necessary by practice, without deviating from the principles and scope of my invention and, of course, within the attached claims.

As shown in attached drawings, the present apparatus consists of plate 10, divided into forward portion 11 and backward portion 12 by the zone of the heel of shoe 13, in process of manufacture.

Both portions 11 and 12 are joined at their lower end by means of hinge 14 or the like, whereby the said portions will have a radial motion, they being able to be raised until they form a more or less obtuse angle, or, plate 10 may be disposed in the apparatus herein described from an entirely plane and straight position to an angular form, with a sufficient grade to be employed in the manufacture of shoes having the highest heels.

On the sides of plate 10 formed by portions 11 and 12, two of which correspond to each of these portions, there are found guide pieces or flanges 15 and 16, one of which is disposed on each side of the said portion, to which become attached the bridges or pressure arches 17 and 18, which freely slide upon the said guide pieces. Bridge 17 can be provided with a shield 19 so as not to damage the cap of shoe 13.

Pneumatic cushion 20 fits over portions 11 and 12 of plate 10, and perfectly covers the gap between both portions, the same as the gap formed by the curved space between the heel and the tread of the shoe, at the shank. This cushion is inflated by passage 21 and valve 22, which regu-

lates the passage of air under adequate pressure, as clearly shown in Fig. 1 of attached drawings. This valve 22 can be provided with handle 23 and can be of such a type as, through the said handle, regulates both the passage of air and the deviation or direction given to the air through the said passage.

Plate 10, composed of portions 11 and 12, rests upon a case made with its section substantially square, as clearly shown in Fig. 1, which case contains the mechanism for raising portion 12 of plate 10 to the desired height. This mechanism substantially consists of rod 24 provided at its forward end with handle or crank 25, and being threaded at its backward end. This rod 24 is held by clamps or guide pieces 27 adequately disposed on the inside of the said case for the mechanism, and the threaded end, which slides over the threaded piece 28, butts against and moves cam 29 mounted and adequately fastened to crosspiece 30 which is also attached to lever 31, the upper surface of which butts against and pushes portion 12 of plate 10 so as to raise it at will, as required by the type of shoe made.

Of course, surface 32 of the case enclosing the mechanism on which plate 10 rests, will be provided with a bore for the passage of the lever 31, and occasionally, with another bore for hinge 14, and will preferably be provided with a lower lid 33 which can be moved by means of hinge 34, so as to give access to the raising mechanism as well as to the passages and valve of the pneumatic cushion. Lower lid 33 is attached to surface 32 by means of screw 35 or the like.

Having thus described the invention what I consider as new and desire to secure by Letters Patent is:

1. An apparatus for pressing soles to shoes comprising a plate, a pneumatic cushion resting on said plate, said plate being divided into two 40 hingedly connected portions whereby one portion

may be adjusted into an angular plane relative to the other portion, the hinge connection between the portions being at the lower parts thereof, said plate portions having side flanges, clamps engageable with a shoe connected to said side flanges, and means for adjusting said adjustable plate portion.

2. Apparatus for applying pressure to shoe soles, comprising a support, a pair of pad supporting plate portions mounted on said support, a hinge connecting adjacent ends of said plate portions, one of said plate portions being adapted to rest flat upon the support and the other plate portion resting upon an angularly movable element pivoted on the support, and mechanism for selectively actuating said movable element to arrange the plate portion resting thereon at a predetermined angular inclination relative to the complementary plate portion, each of said plate portions having flanges at its sides, and clamp engaging means on each side of said flanges.
